UNITED STATES PATENT OFFICE.

FREDERICK W. TAYLOR, OF PHILADELPHIA, PENNSYLVANIA.

GOLF-CLUB.

SPECIFICATION forming part of Letters Patent No. 792,631, dated June 20, 1905.

Application filed August 24, 1904. Serial No. 221,937.

To all whom it may concern:

Be it known that I, FREDERICK W. TAYLOR, a citizen of the United States of America, residing in the city and county of Philadelphia, 5 in the State of Pennsylvania, have invented a certain new and useful Improvement in Golf-Clubs, of which the following is a true and exact description, reference being had to the accompanying drawings, which form a part 10 thereof.

My invention relates to golf-clubs, and particularly to that variety of golf-club known as a "putter," my object being to provide a putter which will enable the strokes made with 15 this club in the game of golf to be made with the greatest accuracy.

The leading feature of my invention consists in providing a putter the shaft of which is provided with two arms diverging from its 20 center line in such a way that these arms or portions of them are adapted to rest against both of the player's arms when the shaft or extensions of the shaft are grasped at an intermediate position between the parts resting 25 on the arms of the player and the head of the club.

Another important feature of my invention lies in the provision in such a club of a strongly-marked center spot or lines which in the swing- 30 ing preliminary motions of the club will furnish to the eye a line of direction by which the motion of the club can be properly aligned with the hole into which it is desired to place the ball. This and other details of my invention will be best understood as described in 35 connection with the drawings, in which they are illustrated, and in which—

Figure 1 represents a player in the act of using my improved club. Fig. 2 is an elevation of the club; Fig. 3, a perspective rear view of the club head and shank, and Fig. 4 a perspective front view of the club head and shank.

A indicates the head of the club, and A' 45 strongly-marked lines placed on the top of the head of the club at its center line, so as to be within full view of the player when using the club.

B is the shank or ferrule of the club, connected with the back of the club through its 50 curved end B', so that the shank extends from the back of the club-head outwardly and up-

wardly, leaving the club-head and its mark A' fully exposed to the player's vision.

C is the shank of the club, which, as shown, 55 is at some distance from the club-head, forked into two arms C' C', these arms again being provided with outwardly-extending arm-rests C² C².

D in Fig. 1 indicates the hole in the golf-ground, and the player illustrated in this figure shows one of the attitudes of the player using my club to put with, the player grasping the shank or its extensions at an intermediate point while the arms C' C' or their extensions 65 C² C² rest against his arms. The motion in this case in using the club is a swinging motion of the arms from the shoulders in and out, the shank and head of the club moving like a pendulum between the player's legs, while the 70 line or center spot A' is directly in the player's vision, enabling him to aline or set his club during its swinging motion and before it comes in contact with the ball.

Having now described my invention, what 75 I claim as new, and desire to secure by Letters Patent, is—

1. A golf-club having a shaft provided with two arms diverging from its center line and adapted to rest against both arms above the 80 hands of the player.

2. A golf-club having a head provided with a shank extending outwardly and upwardly from its back in combination with a shaft secured to said shank and provided with two 85 arms diverging from the center line of the shaft and adapted to rest against both arms above the hands of the player.

3. A golf-club having a head provided with a shank extending outwardly and upwardly 90 from its back and having a clearly-marked center spot on its top, in combination with a shaft secured to said shank and provided with two arms diverging from the center line of the shaft and adapted to rest against both arms 95 above the hands of the player.

4. A golf-club having a shaft C, divided into diverging arms C', C', which arms are provided with outwardly-extending arm-rests C², C², at their upper ends.

FREDERICK W. TAYLOR.
